(No Model.)

J. C. RICHARDSON.
STEAM DROP HAMMER.

No. 248,505.

Patented Oct. 18, 1881.

UNITED STATES PATENT OFFICE.

JULIUS C. RICHARDSON, OF COLUMBUS, OHIO.

STEAM DROP-HAMMER.

SPECIFICATION forming part of Letters Patent No. 248,505, dated October 18, 1881.

Application filed August 29, 1881. (No model.)

To all whom it may concern:

Be it known that I, JULIUS C. RICHARDSON, of Columbus, in the State of Ohio, have invented certain Improvements in Steam Drop-Hammers; and I hereby declare the following to be a full, clear, and exact description thereof, reference being had to the accompanying drawings, making part of this specification, in which—

10. Figure 1 is a vertical section, through the lifting devices, of the improved hammer. Fig. 2 is a vertical cross-section on line $x x$, Fig. 1. Fig. 3 is an enlarged view of the valve. Fig. 4 is a detail, to be referred to.
15. My invention relates to steam drop-hammers; and the object of my invention is to utilize the exhaust-steam which passes from beneath the hammer-piston after the hammer is raised to increase the force of the blow made by the descending hammer, and to construct the hammer so it will deliver rapidly and with short strokes a heavy blow.
20. In the said drawings, A is the base of the machine.

My invention consists in certain details of construction, as hereinafter described and specifically claimed.

In order that those skilled in the art may make and use my invention, I will proceed to describe the manner in which I have carried it out.

30. In the said drawings, A is the base of the machine.

B B are two vertical guide-brackets, between which the hammer-head slides, and which are adjustable backward and forward by means of set-screws C.

The lifting-cylinder D is formed of any desirable pipe, bored true. The base of the cylinder is attached to a small steam-chest, E, in which moves a valve, D', controlled by a bell-crank lever, a, and a rod, b, passing to a lever or treadle at the base or anvil of the hammer. The steam is introduced through pipe d into the steam-chest E, and through port e when the valve is in position, as shown in Fig. 3.

45. The live steam rushes through port e beneath the piston-head and raises the hammer, the piston coming in contact with a cushioning-spring, f, sustained by an adjustable bar, g, secured between two vertical clamping-plates, h, fastened to the head i.

From the end of the steam-chest a large ex-

haust-pipe, G, passes to and opens into the upper end of the cylinder above the piston. The valve D' is bored longitudinally, so as to balance it in the steam-chest E.

Near the upper head, i, the cylinder is provided with trunnions T T, which set in journal-boxes t t, bolted to beams R R.

The operation is as follows: By means of the operative mechanism the valve D' is thrown in the position seen in Fig. 3, whereby the steam-pipe d is connected with the ingress-port e. The steam passing beneath the piston raises the hammer until the piston strikes the spring f. The valve is then changed to the position shown in dotted lines, Fig. 3, cutting off the supply of live steam and opening port e through steam-chest E to exhaust-pipe G. Instantly the steam beneath the piston, acting expansively, is thrown upon the upper surface of the piston as the hammer commences its descent, and thereby aids the delivery of the blow. A diminutive exhaust-pipe, n, is inserted in the upper end of the cylinder, the said pipe being about one-fourth of the area of pipe G and affording an exhaust when the piston again begins to rise. By obviating the placing of the cylinder in a rigid frame connected with the anvil, as has heretofore been done in steam-hammers, I prevent the heavy strains and racking, which so soon renders unserviceable this class of machines. I also do away with all rocker-arms, sliding bevels in the hammer-head, have no attachment to the columns, thereby simply using the treadle-rod for operating the valve. The swinging cylinder enables me to set the anvil over to a degree, if necessary, to make the dies register perfectly.

I have demonstrated by actual tests that with a machine constructed according to my invention I can perform a given amount of work with a cylinder one-third shorter than heretofore necessary, thereby saving steam-power, time, and fuel.

I am aware that heretofore steam-hammers have been made wherein the steam beneath the piston, for raising the hammer, has been suddenly transferred from beneath the piston into the cylinder above the piston to aid the blow as the valve cuts off the live steam, and hence I make no broad claim to such invention.

I am also aware that an oscillating steam-

cylinder, mounted on trunnions at its lower end, has been utilized for operating a radially-moving hammer, and consequently I make no broad claim to mounting the cylinder on trunnions.

I am also aware that steam-hammers of this class have been made wherein an exhaust-pipe has been used above the piston of an equal or greater area than the exhaust-pipe corresponding to my pipe G; but in such construction any good effect of the steam on the upper side of the piston is lost, owing to its full and free access to the air.

Having thus described my invention, what I claim as new, and desire to secure by Letters Patent, is—

1. In a steam-hammer, the cylinder D, pro-

vided with a slide-valve, D', steam-pipe d, port e, and pipe G, in combination with the diminutive exhaust-pipe n, all constructed, arranged, and operated as set forth.

2. The cylinder D, provided with trunnions near its upper end, resting on bearings R, in combination with a piston-rod and a hammer traveling within vertical guides, substantially as described.

3. In combination with the cylinder D of a steam-hammer, the cushioning-spring f, adjustable rod g, and clamping-plates, substantially as described.

JULIUS C. RICHARDSON.
